UNITED STATES PATENT OFFICE.

LUIS CORREA, OF LA FELGUERA, SPAIN.

FURNACE FOR REDUCING ORES.

SPECIFICATION forming part of Letters Patent No. 638,099, dated November 28, 1899.

Application filed January 13, 1899. Serial No. 702,014. (No model.)

To all whom it may concern:

Be it known that I, LUIS CORREA, a subject of the King of Spain, residing at La Felguera, (Oviedo,) Spain, have invented certain new and useful Improvements in Furnaces for Reducing Ores, of which the following is a specification.

This invention relates to furnaces for reducing ores, and particularly lead ores; and it consists in the novel construction of the furnace for carrying out the reduction. The furnace, which operates with gas, is especially adapted for economizing heat.

The construction of the furnace will be described with reference to the accompanying drawings, wherein an embodiment thereof is illustrated.

In the drawings, Figure 1 is a vertical axial section of the furnace in substantially the plane indicated by the line x^1 in Figs. 2, 4, and 6. Fig. 2 is a horizontal section in substantially the plane indicated by the line x^2 in Fig. 1. Fig. 3 is a vertical axial section of the furnace, taken in substantially the plane indicated by the line x^3 in Figs. 2, 4, and 6. Fig. 4 is a horizontal section taken substantially in the plane of the line x^4 in Fig. 3. Fig. 5 is a vertical axial section of the furnace in substantially the plane of the line x^5 in Figs. 2, 4, and 6. Fig. 6 is a horizontal section in substantially the plane of the line x^6 in Fig. 5. Fig. 7 is a vertical axial section of the furnace, taken in the plane indicated by line x^7 in Figs. 2, 4, and 6. Fig. 8 is a vertical axial section of the furnace, taken in the plane indicated by the line x^8 in Figs. 2, 4, and 6. Fig. 9 is a fragmentary plan view of the burner K and adjacent parts.

The furnace is circular in plan, as herein shown, and sunk part way in the ground. These features, however, are not absolutely essential features of the construction. The outer circular wall X is surmounted by a conical roof E, at the apex of which is a louver G to admit air. W is the smelting or reduction chamber or laboratory, which has an arched roof w and a massive bed or hearth O, composed of clay, lime, and coke-dust mixed and well tamped. This hearth O is formed with a hollow or depression at the center to collect the molten metal, as lead, and from this depression a channel leads the lead to a

vertical conduit or well P, formed in the mass of the hearth O, and from this well the lead flows continuously out to an exteriorly-situated well Q, from which it is taken and cast into ingots or pigs. In the wall of the chamber W, at the sides, are charging-doors a, and in the front is a door b for the removal of the scoria. Over the center of the chamber W is the burner K, the operation of which will be hereinafter described. The fumes from the chamber W pass down through conduits A in the wall X, Fig. 5, to the fume-chamber M, Fig. 6, from whence they flow by a conduit B to the condensing-gallery and chimney. (Not shown.)

The fume-chamber M is separated from a hot-air chamber N next above it, Fig. 4, by an arched roof m, and the hot-air chamber is separated from the smelting-chamber W by a strong arched roof n, which supports the hearth O.

The air entering the louver G flows down to the hot-air chamber N through air-flues E, Figs. 3 and 4, formed in the walls, and the heated air from this chamber N flows up to the burner K by way of a horizontal conduit H, an upright conduit I, and a curved connecting-trunk J, (see plan, Fig. 9,) which communicates with the burner K by an inlet. Here the hot air meets and mingles with gas from a holder or generator, this gas flowing to the burner K by way of a gas-conduit R, a pipe S, and a curved connecting-trunk T, Fig. 7, which communicates with the burner K by an inlet.

The hot-air conduit H, Fig. 4, and the fume-conduit B, Fig. 6, both extend into or near to the centers of their respective chambers, so as to receive the gases from the center of the mass in the chamber.

In the fume conduit or flue B draft-regulating devices C and D, Figs. 2, 4, and 8, are provided. These are well-known devices and will need no special description. The gas-conduit R also connects with the flue B near the point where the register D is situated, Fig. 4, and has in it a valve or slide U. The object of this construction is to allow the gas to pass to the chimney instead of to the furnace under certain conditions. The upright conduit I and the upright gas-conduit S will be provided with cut-offs or dampers of the

usual kind. The damper *i* in the conduit *I* is seen in Figs. 2 and 7, and the damper *s* in the conduit *S* is seen in Figs. 2 and 3.

To operate the furnace, it is essential to first 5 heat the chamber *W*. To do this, the air and gas are admitted to the burner *K*, which opens into the top of said chamber, and the mixture of air and gas is then ignited. The flames fill the smelting-chamber and heat it 10 thoroughly. When the chamber *W* has been thus properly heated, the charge of ore, (as lead ore,) fluxing material, and coal is placed therein, the openings closed, and the heat increased. The mass fuses, the ore is gradually 15 reduced, and the lead flows by way of the well *P* and the connecting-conduit to the well *Q*, from which it is dipped or drawn. The scoria floats on the molten mass, and when the lead has been separated and freed from 20 the scoria the latter is removed at the door *b*. The furnace is then recharged as before and the operation repeated. Practically the charges follow each other closely and the operation is substantially continuous.

25 Having thus described my invention, I claim—

1. A gas-furnace for reducing ores, comprising four superposed chambers, namely, an air-receiving chamber, next below this

air-receiving chamber, a smelting-chamber 30 having a hearth, and a burner for gas and air in its upper part, next below the smelting-chamber, a hot-air chamber, connected by flues with the air-receiving chamber and with said burner, and next below the hot-air 35 chamber a fume-chamber, connected with the smelting-chamber and with the fume-outlet, substantially as set forth.

2. A gas-furnace for reducing the ores on a hearth, comprising a smelting-chamber *W*, 40 with a hearth, an air-heating chamber *N*, next below the chamber *W*, a fume-chamber *M*, next below the chamber *N*, and connecting with the smelting-chamber and the fume-outlet, and a burner *K*, open to the upper 45 part of the smelting-chamber, said furnace having also an air-space above the smelting-chamber, air-flues connecting said space with the chamber *N*, and a hot-air pipe *I*, connecting said chamber *N* with the burner *K*, substantially as set forth.

In witness whereof I have hereunto signed my name, this 18th day of December, 1898, in the presence of two subscribing witnesses.

LUIS CORREA.
